VALVE

William J. Baker, Garden Grove, Calif., assignor to Willis Oil Tool Co., Long Beach, Calif., a corporation of California

Filed Oct. 20, 1965, Ser. No. 87,632

Term of patent 14 years

(Cl. D91—3)

FIG. 1 is a view in perspective of a valve, showing my new design;

FIG. 2 is a side elevation thereof; and

FIG. 3 is an end elevation thereof.

I claim:

The ornamental design for a valve, as shown.
